UNITED STATES PATENT OFFICE.

JOHN F. NEWTON, JR., OF BOSTON, MASSACHUSETTS.

FIRE-ESCAPE.

SPECIFICATION forming part of Letters Patent No. 252,130, dated January 10, 1882.

Application filed June 24, 1881. (No model.)

To all whom it may concern:

Be it known that I, JOHN F. NEWTON, Jr., of Boston, in the county of Suffolk and State of Massachusetts, have invented certain Im- 5 provements in Fire-Escapes, of which the following is a specification.

This invention relates to that class of fire-escapes composed of a rope suspended from an elevated point on a building and a device en- 10 gaged with and adapted to slide on the rope and furnish a support for a person descending the rope, the descent of said device being retarded by its friction on the rope.

My invention has for its object to provide 15 certain improvements in a fire-escape of this class, whereby it is made safer, more durable, reliable, and convenient, and is adapted to be quickly regulated by the person descending, so that the friction and resistance will be pro- 20 portioned to the weight of the person.

The invention also has for its object to provide improved means for supporting the rope of a fire-escape of this class from the wall of a building.

25 To these ends my invention consists in the improvements which I will now proceed to describe and claim.

Of the accompanying drawings, forming a part of this specification, Figure 1 represents 30 a perspective view of a fire-escape embodying my invention. Fig. 2 represents a side view of the crane or device that supports the rope. Fig. 3 represents a top view of the same. Fig. 4 represents a side elevation, showing man- 35 ner of suspending the seat. Fig. 5 represents a side elevation with a portion of the casing removed. Fig. 6 represents a section on line $x\ x'$, Fig. 5. Fig. 7 represents a section on line $x'\ x''$, Fig. 5. Fig. 8 represents a section on line 40 $y\ y'$, Fig. 5. Fig. 9 represents a section on line $z\ z'$, Fig. 5. Fig. 10 represents a section on line $z'\ z''$, Fig. 6.

The same letters refer to the same parts in all the figures.

45 In the drawings, a represents a rope adapted to be supported at an elevated point on a building and extend to the ground. I preferably employ as a support for the rope a swinging crane, b , composed of a stout iron bar provided 50 at its outer end with a hook to engage the rope, and bent downwardly at its inner end to enter

bearings formed in lugs $c\ c$ on a plate, d , said plate being securely bolted to the wall.

f represents a box or casing adapted to slide on the rope and form a support for a seat, g , 55 which is suspended from the box in the manner hereinafter described, and so arranged that when a person is sitting thereon the box f will be at the level of the sitter's chest, or thereabout. The box f is provided with devices 60 for maintaining any desired amount of friction on the rope while sliding thereon, so that the rate of its sliding movement may be regulated and the friction adjusted to the weight of the person on the seat.

65 The devices employed to maintain and regulate the friction on the rope are in the present instance composed of four parts.

The first part consists of a pair of pulleys, $i\ i'$, more fully described hereinafter, around 70 which the rope passes in a series of turns and convolutions, and a brake, j , adapted to bear simultaneously upon coinciding peripheral bands or bearing-surfaces $i^2\ i^3$ of the pulleys $i\ i'$, pressed away from said pulleys by a spring, s , 75 (see Fig. 8,) and adapted to be pressed upon the pulleys with any desired degree of pressure by a screw, h , passing through the side of the casing and provided with a suitable handle on its outer end, said screw bearing upon 80 a projection, a' , on the brake, which projection is adapted to move in a guide, l . The bearing-surface of the brake j is preferably covered with rubber or other comparatively yielding material c' .

85 The second part consists of a pair of rollers, $m\ m'$, located at the lower end of the box and adapted to bear on opposite sides of the rope a . The roller m is located in fixed bearings and the roller m' in bearings formed on a movable slide or bar, n , adapted to move toward or from the roller m in a guide, o . A screw, h' , bears on the bar n , and is adapted to force the roller m' toward the roller m , and thus compress the rope to any desired extent. The 90 screw h' and the screw h , bearing upon the brake j , previously described, are in convenient position to be operated by a person on the seat g .

The third part consists of band-brakes to 95 support the seat g and adapted to bear upon the pulleys $i\ i'$, said brakes being composed

of the straps $p p'$, attached to and supporting the seat g and passing through slots $s' s^2$, formed in the bottom of the casing f , and over the upper pulley, i , as shown in Fig. 6. Each strap 5 is provided with a girth or band, b' , encircling the lower pulley, i' , and formed of leather, similar to the straps $p p'$, one extremity of each girth being securely attached to its strap, as shown at t , Fig. 6, and the other extremity of 10 each girth firmly attached to hooks g , projecting from the side of the box f , as shown in Figs. 6 and 10. It will be seen that the weight 15 of a person upon the seat g will cause the straps $p p'$ and their girths to act as band-brakes upon the pulleys $i i'$. It will be obvious that the amount of friction exerted upon the pulleys by the band-brakes will be exactly proportioned to the weight of the person upon the seat g and to the width of the straps composing said 20 band-brakes, or, in other words, with straps of a given width will be greater or less according to the variation in weight of different occupants.

I prefer to limit the width of the straps to 25 about one inch; and in order to avoid increasing said width beyond this limit and to adapt the fire-escape for use by very heavy persons, I provide, fourthly, automatic clamping mechanism, the same consisting of a metallic lever 30 or bar, d' , having a downwardly-bent arm, u , at one extremity and an upwardly-bent arm, u' , at the opposite extremity, said arms being pivoted to the casing f . The bar d' has a groove, 35 d^2 , formed in one side, to admit the rope a , which passes between said bar d' and the roller m . The opposite end of the bar d' is connected with the seat-supporting strap p by means of a strap, p^2 , attached to a link or eye, u^2 , pivoted between two upwardly-projecting ears on 40 the bar d' .

In operation the weight of the occupant of the seat g draws the strap p^2 downwardly, thus causing the bar d' to tip or partially rotate upon its pivots, so as to clamp the rope a between 45 said bar and the roller m . When the seat is relieved from weight the bar d' is returned to its normal position by the action of a spring, s^4 , attached to the casing f , and the link u^2 , thus relieving the rope a from pressure.

50 It may not be necessary in all cases to use all four of the above-described devices. A person of light weight might be able to descend by the use of the brake j alone; and, if desired, the use of the band-brakes $p p'$ and the automatic clamping mechanism may be entirely dispensed with, the seat g in that case being supported by straps, chains, or cords p^2 , suitably attached to the lower part of the box f . The tension of the straps $p p'$ and the straps 55 p^2 may be relatively adjusted and the weight of the occupant of the seat thrown on either set of straps at will by means of suitable buckles, with which the straps may be connected.

60 It will be apparent that by the use of these 65 four devices the friction on the rope and the movement of the box and its pendent seat may

be regulated to any desired extent by a person on the seat.

The pulleys $i i'$ have grooves $r r$ to receive the turns or convolutions of the rope a , and these grooves in one pulley alternate with those in the other, as shown in Fig. 5, the object of this arrangement of the grooves being to keep the turns or convolutions of the rope separate from each other and to prevent them 75 from rubbing and chafing. Each pulley has also a deeper groove, r' , the purpose of these grooves being to guide the rope as it passes onto the pulley i and off from the pulley i' , and prevent the rope from passing at too abrupt 80 an inclination from the pulley i' to the rollers $m m'$ and from the pulley i to the orifice in the top of the box f . This deep groove on each pulley also tends to prevent the rope a from slipping off said pulleys. $i^2 i^4$ represent metal 85 guards attached to the casing f to prevent the straps $p p'$ from slipping off the pulleys.

The operation of my invention as a whole is as follows: A person preparing to descend from an elevated point will first tighten the 90 screws $h h'$ as much as possible. This will make the box f immovable on the rope. The person then seats himself on the seat g and loosens the screws, thus allowing the box to descend, the rate of descent being automatically regulated by the band-brakes $p p'$ and the clamping-bar d' , said rate being exactly proportioned to the weight of the occupant of the seat. If the occupant desires to still further retard the rate of speed or to stop the descent of the box entirely—as, for instance, to 100 avoid a shock in approaching the ground—it may readily be done by means of the screws $h h'$, which are within easy reach of the occupant of the seat.

When the box f has been lowered, if it is desired to raise it again, a person on the ground may hoist it upon the rope a by means of a cord, a^2 , passing over pulleys $v v$, suspended from the crane b and attached to the box f , 110 the screws $h h'$ being loosened so as not to retard the upward movement of the box, and the band-brakes and automatic clamping mechanism being inoperative while the seat is unoccupied. The box f is of such size that it may 115 readily be passed through a window and kept within an apartment ready for use.

$k k$ represent handles for convenience in moving the box, and also to aid the person getting upon the seat. The swinging crane b enables the person to get upon the seat in preparing to descend while said seat is close to the wall of the building, and then by pushing against the wall swing the crane outwardly, and so push the seat from the wall.

125 The seat g is preferably upholstered.

Having thus described my invention, what I claim, and desire to secure by Letters Patent, is—

1. In a fire-escape, the combination of a box 130 or frame having the pulleys $i i'$, provided with alternating grooves and coinciding bearing-

surfaces, a brake adapted to press simultaneously upon said bearing-surfaces to retard the movement of said pulleys, and an adjusting-screw to regulate the pressure of the brake.

5. 2. In a fire-escape, the combination of a box or frame having openings in its opposite ends for the passage of a rope, a pair of pulleys, *i i'*, journaled in said box, a brake provided with an adjusting-screw to retard the movement of said pulleys, and the pair of clamping-rollers located at the lower end of the box and having an adjusting-screw, as set forth.

3. In a fire-escape, the combination of the box or frame having the pulleys *i i'*, the seat *g*, and the supporting-straps adapted to act as band-brakes on the pulleys *i i'*, substantially as and for the purpose set forth.

4. In a fire-escape, the combination of the box or frame having the pulleys *i i'*, adapted to receive upon their peripheries a rope, *a*, passing through said box, the seat-supporting straps adapted to act as band-brakes on said pulleys, and the pivoted lever or bar *d'*, con-

nected with the seat-supporting straps, and adapted to press the rope *a* against a roller *25* journaled in fixed bearings, substantially as and for the purpose set forth.

5. In a fire-escape, the combination of the box or frame having the pulleys *i i'*, adapted to receive upon their peripheries a rope, *a*, *30* passing through said box, a screw-adjusted brake adapted to bear upon portions of the peripheries of said pulleys, the seat-supporting band-brakes adapted to bear upon other portions of the pulleys, and the pivoted lever or *35* bar *d'*, connected with the band-brakes and adapted to press the rope *a* against a roller journaled in fixed bearings, as set forth.

In testimony whereof I have signed my name to this specification, in the presence of two *40* sub-scribing witnesses, this 20th day of June, A. D. 1881.
